(57) **CLAIM**

The ornamental design for a vehicle body, as shown and described.

DESCRIPTION

FIG. 1 is a perspective view of a vehicle body, according to a first embodiment of the invention.

FIG. 2 is a front view thereof.

FIG. 3 is a rear view thereof.

FIG. 4 is left side view thereof.

FIG. 5 is a right side view thereof.

FIG. 6 is a top view thereof.

FIG. 7 is a perspective view of a vehicle body, according to a second embodiment of the invention.

FIG. 8 is a front view thereof.

FIG. 9 is a rear view thereof.

FIG. 10 is left side view thereof.

FIG. 11 is a right side view thereof, and,

FIG. 12 is a top view thereof.

Mirror images of opposite side views are within the scope of the claimed design even if not illustrated.

Features shown in broken lines do not form part of the claimed design.

1 Claim, 12 Drawing Sheets
